UNITED STATES PATENT OFFICE.

EMANUEL AUFIERO, OF BROOKLYN, NEW YORK, ASSIGNOR TO AUTOMOBILE SUPPLY MFG. CO., OF BROOKLYN, NEW YORK, A CORPORATION OF NEW YORK.

SIGNALING APPARATUS.

1,198,988.

Specification of Letters Patent. Patented Sept. 19, 1916.

Application filed August 24, 1911, Serial No. 645,863. Renewed January 31, 1916. Serial No. 75,468.

To all whom it may concern:

Be it known that I, EMANUEL AUFIERO, a citizen of the United States, residing at Brooklyn, in the county of Kings and State of New York, have invented a new and useful Signaling Apparatus, of which the following is a complete specification.

My invention relates to diaphragm actuated alarms, such as are used on automobiles, 10 motorboats and the like; and has for its object the construction of an improved device of this class.

In Figure 1, is shown a partly sectional view of a signal embodying my invention; 15 Fig. 2, shows adjusting means for the displacing member; Fig. 3, shows a preferred way of fastening rotary member and impact piece. I have found that very desirable results are attained when the operating members are so constructed, that the diaphragm 20 is apt to vibrate as a whole without formation therein of ripples or other secondary vibrations: I have found very efficient the use of a disk 17 (Fig. 1) provided with cam 25 projections and fastened to the diaphragm 4; a similar disk 16 mounted on the armature shaft 12 of the electric motor 10 is used to simultaneously engage the projections of the first named disk and to vibrate the dia- 30 phragm. This construction permits compactness of design and eliminates the displeasing rattling of similar devices where a single point of contact is used in vibrating the diaphragm, or where a number of contacting points contact successively, not simultaneously with a number of projections carried by the diaphragm. I preferably use cam projections having gradually increasing 35 pitch in one way on one disk, and cam pro- 40 jections of increasing pitch in the opposite way in the other disk. The impact piece 17 may be secured to the diaphragm by means of screw 19 and nut 18, or any other suitable means. The front casing 2 may carry the 45 resonator 20, or may have a plain opening for the escape of sound; and the diaphragm may be clamped between cushioning washers 3. For sound-adjustments I preferably 50 mount the armature shaft 12 so that it can be moved perpendicularly to its plane of rotation. A thrust bearing may be used composed of a screw 14 carried by frame 13, and a nut 15 may be used to lock said screw when adjusted—by advancing said screw 14 55 back and forth the amount of engagement

of the rotary member 16 with the impact piece 17 may be easily regulated. The motor carrying arm 6 extending from the main frame 5, has an oblong hole 8 apt to receive screw 7 holding the motor 10. A nut 9, or any other suitable means may be used to lock said screw 7 when the motor has been adjusted to the exact distance from the diaphragm by means of said oblong hole permitting to and fro adjustments of the 60 motor.

In Fig. 2, another preferable mode of adjustment is disclosed which permits the armature to remain in the same lines of force of the field magnets, while an adjustable 70 member 25 provided with a threaded part 26 runs through said armature shaft 24, which rests between the stationary bearings 22 and 23 carried by the frame 21. The displacing member 16, as seen, is mounted directly on said adjustable member 25, and a jam-nut 27 may be used to hold said adjustable member at the desired distance from the diaphragm. A very efficient and economical way of mounting the operating 75 disks is to provide them with self tightening screws.

In Fig. 3, shaft 34 carries the threaded part 33 meshing with disk 32; the dia- 80 phragm 4 carries a threaded member 28 se- cured to the diaphragm by means of rivet 29 or other suitable means and the other disk 31 is fastened to said member by means of the male screw 30. It is easily understood 85 that the threads are so disposed that rotation of disk 32 in engagement with disk 31 90 serves to tighten the engagement with each screw.

I find very desirable the use of a cork washer 35, or any other cushioning material 95 between the impact piece and the dia- phragm, as it prevents an unclear sound produced by the slight unevenness of the contacting surfaces of the disks 31 and 32.

Various modifications, transpositions and 100 changes may be resorted to without departing from the scope of my claims.

What I claim is:

1. A signaling-device, comprising the combination of an acoustic plate, a rotary 105 electric motor having a hollow armature- shaft disposed at an angle to said plate, a longitudinally-adjustable member located in said shaft and having one end protruding therefrom, means for locking said member 110

- in the desired adjustment, and a plate-actuating device carried by said protruding end and actuating said plate.
2. In a horn or signaling device, a diaphragm, actuating means for mechanically agitating the diaphragm, including a motor having a hollow armature shaft, and an adjustable diaphragm-displacing member provided with a stem extending into the bore 10 of said shaft and adjustably secured fast thereto, whereby relative adjustment of the diaphragm and diaphragm displacing member may be effected.
3. The combination of an acoustic diaphragm, an electric rotary motor, a hollow armature shaft for said motor, a member extending through said shaft and adjustably 15

secured fast thereto, and diaphragm displacing means mounted on said member.

4. The combination, in a signaling-device, 20 of a diaphragm, and mechanical vibrating means therefor comprising the combination of a hollow rotary driving-shaft mounted in suitable bearings, a longitudinally-adjustable shaft located longitudinally within said 25 hollow shaft, means for securing it at desired adjustment therein, and displacing means carried by said shaft to act upon said diaphragm.

EMANUEL AUFIERO.
